UNITED STATES PATENT OFFICE.

JOHN F. MALLINCKRODT, OF DENVER, COLORADO, ASSIGNOR, BY DIRECT AND MESNE ASSIGNMENTS, TO THE SAUVAGE DUPLEX AIR BRAKE COMPANY, OF DENVER, COLORADO.

FLUID-BRAKE MECHANISM.

SPECIFICATION forming part of Letters Patent No. 710,876, dated October 7, 1902.

Application filed January 13, 1902. Serial No. 89,572. (No model.)

To all whom it may concern:

Be it known that I, JOHN F. MALLINCKRODT, a resident of Denver, in the county of Arapahoe and State of Colorado, have invented certain new and useful Improvements in Fluid-Brake Mechanism; and I do hereby declare the following to be a full, clear, and exact description of the invention, such as will enable others skilled in the art to which it appertains to make and use the same.

My invention relates to an improvement in fluid-brake mechanism, the object of the invention being to provide improved mechanism for governing the fluid-pressure in the brake-cylinders.

With this object in view the invention consists in certain novel features of construction and combinations and arrangements of parts, as will be more fully hereinafter described, and pointed out in the claims.

In the accompanying drawings, Figure 1 is a view illustrating my improvements attached to a car, and Fig. 2 is an enlarged view in section illustrating the governor.

1 represents the spring-supported car-body, and 2 the sand-board, which is relatively stationary. Fulcrumed to the under side of the car-body 1 is a bell-crank lever 3, to one arm of which a link or rod 4 is connected and secured at its lower end to the sand-board. A rod or link 5 connects the other member of lever 3 with one member of a similar bell-crank lever 6, fulcrumed to the car-body. The other member of lever 6 is connected to stem 7, which passes through an opening in an externally-threaded sleeve 8, the lower end of which latter normally engages a flange 9, fast on stem 7. This sleeve is screwed into a nut 9^a in the upper end of a cylinder 13, and the flange 9 bears against the upper end of a coiled spring 10, whose lower end bears upon a piston 11, fast on the piston-rod 12 of my improved governor-valve. The piston 11 is mounted in the cylinder 13, above referred to, and the latter and all the working parts of the governor are inclosed in a block or casing 14, supported in front of the brake-cylinder 15 and in the passage of the fluid from the triple valve. From

the triple valve the fluid passes into a duct 16, and the latter is connected with a similar duct 17 above the same and leading to the brake-cylinder by a ring 18, supported directly below the cylinder 13, forming a valve-seat, through which the rod 12 projects, and has secured on said rod below the ring 18 a valve 19, provided with suitable packing 20 to firmly seat against the ring 18 when the valve is raised by the piston. The extreme lower end of rod 12 is made with a circular head 21, mounted in a cylindrical casing 22, secured in place by nut 23 to hold the rod at all times against lateral movement.

The bottom of the cylinder 13 is closed, with the exception of an opening 24, through which the piston-rod 12 passes, and this rod fits comparatively close in said opening, but not airtight. The bottom of the cylinder 13 serves to retard the entrance of sufficient fluid-pressure into said cylinder to operate the valve 19 until the brake-cylinder shall have been filled and the pressure therein and in the ducts shall have risen to a certain point, at which time sufficient pressure will have accumulated in the cylinder 13 through the opening 24 and past the rod 12 to exert enough upward pressure on the piston 11 to close valve 19 and entirely shut off the supply of air or other fluid to the brake-cylinder.

It will be seen that with my improvements the valve 19 does not begin to close until after a certain pressure is in the brake-cylinder and ducts 16 and 17, and hence the flow of air or other fluid is not retarded by a partial closing of the valve until a sufficient amount of fluid has entered the brake-cylinder, when the valve will be closed by the fluid entering the cylinder 13 around the piston-rod, thus constituting a quick-acting valve and permitting quick action of the brakes.

With the improvements above described it will be seen that the relative load on the car will regulate the tension of spring 10 through the medium of the bell-crank levers 3 and 6 and rods 4 and 5, connected with the sand-board 2 of the car and adapted to raise or lower the stem 7, according to the weight on the car.

To permit the exhaust of the fluid from the brake-cylinder and the ducts 16 and 17, a spring-pressed valve 25 of the usual construction is provided, normally closing a 5 port 26 between the ducts 16 and 17.

Various slight changes might be resorted to in the general form and arrangement of the several parts described without departing from the spirit and scope of my invention, 10 and hence I would have it understood that I do not wish to limit myself to the precise details set forth, but consider myself at liberty to make such slight changes and alterations as fairly fall within the spirit and scope of 15 my invention.

Having fully described my invention, what I claim as new, and desire to secure by Letters Patent, is—

1. In a fluid-pressure brake system, the 20 combination with a valve interposed between the pressure source and the brake-cylinder to control the passage of pressure from one to the other, of a cylinder, a spring-pressed piston therein, a rod connecting the piston 25 with said valve and means for retarding the admission of fluid into said cylinder, whereby sufficient pressure will not have accumulated in said cylinder to close the valve until the brake-cylinder shall have become filled.

2. In a fluid-pressure brake system, the 30 combination with a cylinder having an opening in one end, a spring-pressed piston in said cylinder, a piston-rod secured to the piston and projecting through the opening in the 35 end of the cylinder, said opening being of a size relatively to the piston-rod to retard the passage therethrough of fluid, ducts beneath said cylinder and a valve operated by said piston to close the passage through said ducts 40 when a predetermined quantity of fluid squeezes into the cylinder between the opening in the end thereof and the piston-rod.

3. In a fluid-pressure brake system, the 45 combination with a cylinder located in the passage of the fluid to the brake-cylinder, said first-mentioned cylinder having an opening in one end of just sufficient size to permit the movement of a piston-rod, a piston in said cylinder, a rod secured to said piston and 50 projecting through the opening in the end of the cylinder, ducts below the cylinder for the passage of fluid to the brake-cylinder, and

said ducts communicating with the opening in the end of the first-mentioned cylinder, a valve carried by the piston-rod and adapted 55 to close the fluid-passage to the brake-cylinder when the piston is raised by the fluid squeezing between the piston-rod and the end of the cylinder.

4. In a fluid-brake system, the combination 60 with a cylinder closed at its ends and a fluid-passage below one end thereof to the brake-cylinder, of a piston in said first-mentioned cylinder, a piston-rod secured to said piston and projecting through an opening in one end 65 of the cylinder and practically filling said opening, of a valve operated by said piston-rod to close the fluid-passage when the piston is moved by fluid forcing its way into the cylinder around the piston-rod. 70

5. In a fluid-brake system, the combination with a cylinder having a spring-pressed piston therein and a mechanism operated by the weight of the car for regulating the tension of said spring, of ducts for the passage of 75 fluid to the brake-cylinder, communicating with one end of said first-mentioned cylinder, a piston-rod secured to said piston and projecting through the end of the cylinder, means for retarding the entrance of fluid into the 80 first-mentioned cylinder, and a valve carried by the piston-rod and adapted to close the passage through the ducts when a sufficient amount of fluid has squeezed into the cylinder around the piston-rod and moved the piston. 85

6. A governor for fluid-brake systems consisting of a cylinder to be located in the fluid-passage to the brake-cylinder and having a spring-pressed piston therein, a piston-rod secured to the piston and projecting through 90 the end of the cylinder and into the fluid-passage, means for retarding the flow of fluid from said fluid-passage to the first-mentioned cylinder, and a valve operated by said rod to close the passage when sufficient pressure 95 shall have accumulated in the first-mentioned cylinder to move the piston therein.

In testimony whereof I have signed this specification in the presence of two subscribing witnesses.

JOHN F. MALLINCKRODT.
